AUTOMATIC CONTROL DEVICE FOR
IGNITION TIMERSMarion Mallory, Toledo, Ohio, assignor to The
Mallory Research Company, a corporation of
Delaware

Application October 19, 1931, Serial No. 569,690

10 Claims. (Cl. 123—117)

This invention relates to a device for automatically controlling the timing of the ignition in internal combustion engines in accordance with the various conditions of operation.

Automatic ignition timing devices, as heretofore used, have depended upon an increase in the speed of the engine or upon an increase in the degree of vacuum in the intake passageway for initially advancing the spark. In order to insure a smooth and steady operation when the engine is idling, it is necessary to set the timer so that the spark will occur when the crank is 5° to 10° past dead center. With such setting, when the throttle is first opened, if the initial spark advance depends directly or indirectly upon an increase in speed, the pick up will necessarily be slow. On the other hand, if the spark is initially set where it should be for the best performance after the throttle is open, it will cause the operation of the engine to be jerky when idling or perhaps to stop altogether.

With the above facts in mind it is the object of the present invention to provide a double acting control device, preferably a device which will retard the timing only when the engine is idling with the throttle closed, permitting it to advance immediately to normal as soon as the throttle is opened, so as to insure a quick pick up, and which will thereafter gradually advance the timing as the vacuum in the intake passageway increases or as the speed of the engine increases.

My invention will be more particularly described in connection with the accompanying drawings, in which—

Figure 1 is a sectional view of the timer with the control device associated therewith;

Figure 2 is a section taken on the line 2—2 of Fig. 1;

Figure 3 is a view similar to Fig. 1 but showing a modified form; and

Figure 4 represents a chart showing the spark advanced as the throttle is opened and the speed of the engine increases.

As shown in the drawings the invention is associated with an ignition timer comprising a housing 10 formed with a bearing 11 for the timer shaft 12. As shown in Figs. 1, 2 and 3 a sleeve 13 is mounted for relative circumferential movement on the shaft 12 and is provided with a cam 14 which actuates the circuit breaker 15. The relative position of the sleeve 13 and cam 14 with reference to the timer shaft 12 is controlled through the medium of a circular plate 16 which is secured to the sleeve by screws 17 or other suitable means.

In the form of the invention shown in Figs. 1 and 2 a plate 18 is secured to the shaft 12 and is provided with a stud 19 which projects into an arcuate slot 20 formed in the plate 16. A spring 21 is mounted on the plate 16 and bears against the stud 19 so that it has a tendency to advance the plate 16 in its relation to the timer shaft as the latter rotates in a right hand or clockwise direction as indicated by the arrow.

In order to modify the operation of the timer as affected by the spring 21, the housing 10 is formed with an extension 22, within which is a reciprocable brake member 23 adapted, under predetermined conditions, to engage and retard the rotation of the disk 16. The brake member 23 has a stem 24 which extends into a housing or cylinder 25 secured to the extension 22 and is there provided with a piston 26. The brake is urged toward engagement with the disk 16 by a spring 27 the tension of which may be adjusted by a thumb screw 28. In addition to the spring 27, the piston 26 may be acted upon by suction through either of the passageways 29 or 30 which, by means of a three-way valve 31 are selectively placed in communication with the intake passageway 32 of the engine through a connecting conduit 33.

For shifting the valve 31, the latter is provided with a crank arm 34 which is connected by a link 35 to a crank arm 36. The throttle valve 37 is secured to a pin 38 on which the crank 36 is mounted. A lever 39 is secured to the pin 38 and a spring 40 connected therewith urges the valve to a closed or idling position with the lever engaging a stop pin 41. The crank 36 has a lug 42 which engages the other end of the lever 39 to open the throttle valve. The crank 36, however, has a lost motion connection with the lever 39 and in closing the throttle is moved to the position shown in broken lines in Figs. 1 and 3, while the lever 39 stops as soon as it engages the stop pin 41.

In the form shown in Fig. 3 the construction and operation of the brake and the means for controlling the same are the same as in Fig. 1 but a centrifugal governor is substituted for the spring 21. This centrifugal governor comprises a weight 43 eccentrically pivoted on a plate 44 secured to the timer shaft 12. The outer end of this weight has a lug 45 which projects through an arcuate slot 46 in the plate 44 thus limiting the movement of the weight in either direction about its pivot. The lug 45 also projects into an eccentric slot 20a in the plate 16 so that, with the timer shaft rotating in a right hand or clock-

wise direction as indicated by the arrow, the outward movement of the weight under the influence of centrifugal force will advance the plate 16 and the cam 14. This outward movement of the weight is opposed by a spring 47 carried by the plate 44 and its inward movement is opposed by a spring 49. The weight 43 normally comes to rest in an intermediate position as shown in Fig. 3 with the springs 47 and 49 resting against stops 48 and 50 respectively.

In the operation of the invention as illustrated, when the throttle is closed with the crank arm 36 in the position shown by broken lines, the valve 31 will be in such position that the passageway 29 will be in communication with the intake passage 32 of the engine. With the throttle closed, a high vacuum will be established in the intake passageway and will augment the effect of the spring 27 on the piston 26, causing the brake member 23 to bear against the disk 16 with such force that the spark has a maximum retardation. In order to obtain the most favorable results, the setting is such that this maximum retardation causes the spark to occur when the crank is 5° or 10° past dead center. As the crank arm 36 is advanced to the full line position shown in Figs. 1 and 3 to open the throttle, the passageway 29 is cut off from the intake 32 and there is then no pressure of the brake upon the disk 16 except that caused by the spring 27. This permits the spark to advance immediately about 20°, as indicated by the line 51 in Fig. 4, as soon as the throttle commences to open. This insures a quick pick up and, as the throttle is opened wider for an increase in speed, the passageway 30 is brought into communication with the intake 32 and the increased vacuum, as the speed of the engine increases, gradually counter-acts the effect of the spring 27, the brake member 23 bears with less and less pressure against the disk 16, gradually advancing the spark, as indicated by the line 52 in Fig. 4, until the pressure of the brake upon the disk 16 ceases altogether and the timing reaches the maximum advance permitted by the slot 20 or 20°.

From the foregoing description, it will be seen that I have provided a timer controlling device which may be initially set so that, in idling, the spark will occur after the crank passes dead center, thus insuring a smooth and steady operation, and yet, the moment the throttle starts to open, the spark is immediately advanced sufficiently to insure a quick pick up, after which the spark is advanced gradually in accordance with the amount of vacuum in the intake passageway as determined by the speed of the engine and the position of the throttle.

It will be understood that the invention is not limited to the structure shown and described but includes all such modifications as may fall within the scope of the appended claims.

What is claimed is:

1. In an ignition timer, means including a brake for effecting an extreme retardation of the timing while the throttle is in idling position, and means to lessen the frictional resistance of the brake for effecting an immediate advance of the timing through a substantial angle as soon as the throttle starts to open and before there has been any appreciable increase in speed.

2. In an ignition timer, a timer shaft, a circuit breaker cam having a relative circumferential movement thereon to vary the timing, a spring tending to advance the cam, a brake tending to retard it, means constantly acting on the brake

and operable by itself to effect an intermediate timing, and supplementary means for modifying the effect of said constantly acting means to cause a progressive release of the brake as the speed increases and to increase the pressure of the brake when the engine is idling.

3. In an ignition timer, a timer shaft, a circuit breaker cam having a relative circumferential movement thereon to vary the timing, a spring tending to advance the cam, a brake tending to retard it, means constantly acting on the brake and operable by itself to effect an intermediate timing, and supplementary means for rendering the vacuum of the engine intake passage effective to progressively lessen the effect of the brake as the speed of the engine increases and to increase the effectiveness of the brake when the engine is idling.

4. In an ignition timer, a timer shaft, a circuit breaker cam having a relative circumferential movement thereon to vary the timing, a spring tending to advance the cam, a brake tending to retard it, a piston connected with the brake, means constantly acting on the piston to apply the brake with moderate force to effect an intermediate timing, and means for rendering the vacuum of the engine intake passage effective upon the piston to progressively diminish the pressure of the brake as the speed of the engine increases and to increase the pressure of the brake when the engine is idling.

5. In an ignition timer, a timer shaft, a circuit breaker cam having a relative circumferential movement thereon to vary the timing, centrifugal means tending to advance the cam, a brake tending to retard it, means constantly acting on the brake and operable by itself to effect an intermediate timing, and supplementary means for modifying the effect of said constantly acting means to cause a progressive release of the brake as the speed increases and to increase the pressure of the brake when the engine is idling.

6. In an ignition timer, a timer shaft, a circuit breaker cam having a relative circumferential movement thereon to vary the timing, centrifugal means tending to advance the cam, a brake tending to retard it, means constantly acting on the brake and operable by itself to effect an intermediate timing, and supplementary means for rendering the vacuum of the engine intake passage effective to progressively lessen the effect of the brake as the speed of the engine increases and to increase the effectiveness of the brake when the engine is idling.

7. In an ignition timer, a timer shaft, a circuit breaker cam having a relative circumferential movement thereon to vary the timing, centrifugal means tending to advance the cam, a brake tending to retard it, a piston connected with the brake, means constantly acting on the piston to apply the brake with moderate force to effect an intermediate timing, and means for rendering the vacuum of the engine intake passage effective upon the piston to progressively diminish the pressure of the brake as the speed of the engine increases and to increase the pressure of the brake when the engine is idling.

8. In an ignition timer, a timer shaft, a circuit breaker cam having a circumferential movement thereon to vary the timing, means tending to advance the cam, means including a brake for effecting an extreme retardation of the timing at idling speeds, and means to lessen the frictional resistance of said brake to effect an immediate advance of the timing through a substantial an-

gle immediately before the throttle is opened and before there has been any appreciable increase in speed.

9. In an ignition timer, centrifugal means tending to advance the time of the break, friction means tending to retard the time of the break, means to utilize suction from the engine to decrease the effect of said friction means as the speed increases and to increase the effect of 10 said friction means at idling speeds, and means including a lost motion connection to cut off said suction means at idling speeds to lessen the resistance of said friction means to effect an im-

mediate advance of the timing through a substantial angle immediately before the throttle is opened and before there has been any appreciable increase in speed.

10. In an ignition timer, a timer shaft, a circuit breaker cam having a circumferential movement relative thereto to vary the timing, means tending to advance the cam, means including a brake tending to retard the cam, and means to utilize suction from the motor to add to or subtract from the effective resistance of said brake means.
